UNITED STATES PATENT OFFICE.

GEORGE S. LEMON, OF WALKER, WEST VIRGINIA.

WRENCH.

1,186,668.

Specification of Letters Patent. Patented June 13, 1916.

Application filed October 16, 1915. Serial No. 56,809.

To all whom it may concern:

Be it known that I, GEORGE S. LEMON, a citizen of the United States, residing at Walker, in the county of Wood and State of West Virginia, have invented certain new and useful Improvements in Wrenches; and I do hereby declare the following to be a full, clear, and exact description of the invention, such as will enable others skilled in the art to which it appertains to make and use the same.

This invention relates to new and useful improvements in wrenches and more particularly to that class of wrenches used for joining lengths of pipe of the larger diameter.

Another object of the invention is to provide a wrench having a rotatable jaw provided with a plurality of ratchet teeth for use in connection with a wrench lever to enable the jaw to be rotated.

A further object of the invention is to provide a novel form of rotary jaw for gripping the end of the pipe to be turned which may be readily placed in position or removed from the pipe and which will effectively grip the same and prevent the pipe from turning with relation thereto.

With these and other objects in view, the invention consists in the novel combination and arrangement of parts which will be fully set forth in the following specification and accompanying drawings, in which:

Figure 1 is a bottom plan view of a wrench constructed in accordance with this invention, Fig. 2 is a side view of the wrench. Fig. 3 is a vertical sectional view through the wrench. Fig. 4 is a detail view of one of the jaw members, illustrating the gripping jaw, and Fig. 5 is a detail view of the movable support for the pivot bar.

Referring to the drawings, the numeral 1 designates the base member of the frame of the device provided with the forwardly extending arms 2. These arms are provided at their outer ends with the curved recesses 3, the inner ends of which are offset as at 4 to receive the clamping shoe 5. This clamping shoe is provided with a serrated jaw face 6 and is pivotally mounted as at 7 on the short end 8 of a lever 9 which is pivoted as at 10 to its respective arm. The long end of the lever extends toward the base 1 and it will be apparent that when the same is moved downwardly in the direction of the arrow as indicated in Fig. 2, the jaw mem-

ber or shoe will be moved into clamping position.

Extending between the arms 2 at a point spaced outwardly a short distance from the base 1 is the pivot bar 11, which supports the actuating lever designated generally by the numeral 12. This lever 12 comprises the handle portion 13 formed at its lower end with the head 14 and one side of this head is recessed as at 15 at a point above the pivot opening 16, while the opposite side of the head is provided with a recess 17 at a point below the pivot opening 16. This pivot opening 16 receives the pivot bar 11 and forms a center around which the handle 13 swings. Pivotaly mounted within the recess 15 is a pawl 18, the outer end of which is bent downwardly as at 19, and this pawl coöperates with the pawl 20 which is mounted in the recess 17 and has its end bent downwardly as at 21. These pawls 18 and 20 are arranged to engage the rotatable jaw member so that upon oscillation of the lever, the same will be turned. In order to limit the downward movement of the pawls, there are provided the flexible members 22, which are connected as at 23 to the pawls and as at 24 to the handle 13. It will thus be seen that upon movement of the handle, beyond a predetermined point, the pawls may be lifted so as to disengage the ratchet teeth of the jaw.

The jaw above referred to consists of the semicircular jaw members 25 and 26, each of which is formed with a plurality of peripheral ratchet teeth 27 and a central angular flange 28, which is adapted to hold the pawls in place on the jaw members. These jaw members are connected together at one end by a suitable link 29 and the opposite ends are connected by the hooks 30, one of which is provided with the thumb piece 31. A recess 32 is formed in the jaw member 26 and mounted in said recess is the shoe 33, provided with a serrated jaw face 34 which is adapted to grip the pipe upon which the device is used to lock the rotatable jaw thereon and against relative movement. This shoe 33 has connected centrally thereto as at 35, a link 36, the opposite end of which is pivoted as at 37 to the jaw member 26 and upon reference to Fig. 3, it will be noted that upon inward movement of the shoe, the same will firmly grip the pipe on which the device is used. In order to move the shoe inwardly, there is provided a link

38 which is pivoted to the pivot 35 and the opposite end of said link is pivoted as at 39 to the lever 40 which in turn is pivoted as at 41 to the jaw member 26. It will thus be seen that upon movement of the lever, the shoe 33 may be made to engage or disengage the pipe according to the direction of movement. In order to hold the jaw in proper position for opening, there is provided a plurality of lugs or pins 42, which extend outwardly from one side of the jaw and which are adapted to be engaged by the hooks 43 on the end of the arm 44 and it will be seen that this arm may be swung into the dotted line position in Fig. 3, so as to hold the jaw against turning during the opening operation.

In order to prevent the pivot bar 11 from springing downwardly when excessive pressure is brought on the lever 14, there is provided the movable support designated generally by the numeral 45 consisting of the body 46, provided at one end with the opening 47 for the reception of the pivot bar 11 and the opposite end is provided with the handle member 48 which forms at the point where it joins the body 46, a shoulder 49 for engagement with the base 1. It will thus be seen that when the shoulder 49 engages the base 1, the bar 11 cannot be moved inwardly toward said base regardless of the amount of strain thereon and thus any springing of the bar will be eliminated.

It will be apparent from the foregoing that in use, the device is assembled as illustrated in Figs. 1, 2, and 3 and upon oscillation of the lever 13, the jaw will be revolved, thus turning the length of pipe which is held therein and threading the same into the socket of the pipe to which it is to be joined, the last named pipe being held stationary by one of the shoes 5 by the manual manipulation of the lever supporting the same. It will be understood that only one of the jaws 5 is clamped at a time thereby allowing the pipe to freely rotate in the opposite jaw. In this way, it will be seen that pipes of large diameters may be readily connected and the necessity of providing extra large wrenches is eliminated.

While in the foregoing, there has been shown and described the preferred embodiment of this invention, it is to be understood that such changes may be made in the combination and arrangement of parts as will fall within the spirit and scope of the appended claims.

What is claimed is:—

1. A wrench of the class described com-

prising a U-shaped frame, jaws at the ends 60 of the arms of the frame, a rotatable jaw adapted to surround the pipes being connected, said pipes being held in the jaws in the arms of the frame and means to rotate said rotatable jaw. 65

2. In a pipe wrench, a U-shaped frame, jaws at the ends of the arms of the frame adapted to support the pipes to be connected, a rotatable jaw surrounding said pipe, a plurality of ratchet teeth on the periphery of the rotatable jaw, a lever pivoted on the frame and pawls carried by the lever for engagement with the ratchet teeth on the rotatable jaw whereby upon oscillation of the lever the jaw will be rotated. 70

3. In a pipe wrench of the character described a U-shaped frame, jaw members supported at the outer ends of the arms of the frame, said jaw members being adapted to hold the pipes which are to be connected, 80 a rotatable jaw member adapted to be clamped around one of said pipes, ratchet teeth on the periphery of the rotatable jaw, a lever pivoted to the frame, pawls pivoted to the lever and adapted to form a means for 85 rotating the rotatable jaw and a pipe gripping shoe within the rotatable jaw for engaging the pipes and preventing the same from turning with relation to the rotatable jaw. 90

4. In a pipe wrench, a U-shaped frame, the arms of said frame being provided with recesses near their outer ends, the recesses being adapted to receive the pipes which are to be connected, a sliding shoe for engaging 95 said pipes for holding the same in place in the recesses, a lever for actuating the shoe, a rotatable jaw member adapted to be clamped around one of the pipes, ratchet teeth on the periphery of the jaw member, 100 said jaw member being separable and having a recess in one of its sections, a shoe slideable in said recess and adapted to grip the pipe upon which the device is used to prevent the pipe from turning with relation 105 to the jaw, a lever pivoted in the frame, pawls pivoted to the lever and adapted to engage the ratchet teeth to rotate the jaw member upon oscillation of the lever, and means to prevent the pawls from moving 110 beyond a predetermined distance.

In testimony whereof I affix my signature in presence of two witnesses.

GEORGE S. LEMON.
